ATTORNEYS.

UNITED STATES PATENT OFFICE.

GEORGE H. HOHNSBEEN, OF MINNEAPOLIS, MINNESOTA, ASSIGNOR OF THREE-FIFTHS
TO J. D. BROWN, OF MINNEAPOLIS, MINNESOTA.

DISPENSER.

1,293,438.

Specification of Letters Patent.

Patented Feb. 4, 1919.

Application filed March 8, 1917. Serial No. 153,376.

To all whom it may concern:

Be it known that I, GEORGE H. HOHNSBEEN, a citizen of the United States, resident of Minneapolis, county of Hennepin, and 5 State of Minnesota, have invented certain new and useful Improvements in Dispensers, of which the following is a specification.

My invention relates to dispensers and particularly to dispensers of liquid soap, and 10 the object of the invention is to provide a liquid soap dispenser, which shall be simple and convenient in its operation.

A further object is to provide a dispenser of simple sanitary construction and one in 15 which the flow of the contents may be adjusted.

Other objects of the invention will appear from the following detailed description.

The invention consists generally in various 20 constructions and combinations, all as hereinafter described and particularly pointed out in the claims.

In the accompanying drawings forming part of this specification,

25 Figure 1 is a top view of a dispenser embodying my invention,

Fig. 2 is a longitudinal cross-sectional view,

Fig. 3 is a front view.

30 In the drawing, 2 represents a cup or container which is preferably the shape of a hemisphere. A lug 3 is mounted in the inside of the container 2 being cast integrally therewith. The lug 3 supports a coiled

35 spring 4, which is seated against the inside of the container 2. A shoulder 5 is provided around the edge of the container 2 on which is seated a diaphragm cover 6, preferably of thin, flexible metal. The cover 6 is fastened

40 to the container 2 by soldering, brazing or other suitable means. A nipple 7 is inserted in the side of the container 2, said nipple being provided with an orifice 8. 9 represents the liquid contents of the container,

45 and said contents may be forced from the container through the orifice by pressing inwardly on the diaphragm cover 6, which after inward pressure is released thereon resumes its normal position by reason of its

50 flexible construction, aided by the outward pressure of the spring 4. The flow of the contents 9 through the orifice 8 may be regulated by means of an adjustable screw 10 seated in the inward end of the nipple 7.

55 A pair of lugs 11 is provided opposite the

nipple 7 on the outside of the container 2 and cast integrally therewith. By means of said lugs 11 and a screw 12 the container 2 is coupled to the end of an arm 13. The other end of said arm is supported by the 60 projecting flanges 14 of a plate 15, which is secured by screws 16 or other suitable means to any convenient support 17, such as the wall of a room. The arm 13 is fastened between the flanges 14 by means of a screw 65 18 passing through a hole 19 in the end of said arm, which is free to oscillate in a horizontal plane, as indicated by the dotted lines in Fig. 1. If desired, the arm 13 may be held in a rigid position by withdrawing the 70 screw 18, pushing the end of the rod into the recess 20 in the plate 15 and then inserting the screw 18 through the hole 21.

In its normal position the container 2 hangs below the arm 13, as shown in Figs. 2 75 and 3. To fill said container, it may be swung upwardly above said arm, the nipple 7 removed by means of a wrench, and the liquid poured therein through the opening.

I claim as my invention:

1. A soap dispenser comprising an arm having means for mounting it in a horizontal position on the wall, a cup pivoted on said arm and having a diaphragm-like cover and adapted to contain a supply of soap, the 85 lower wall of said cup having a soap discharge orifice through which the soap is delivered when pressure is applied to said diaphragm.

2. A liquid soap dispenser comprising a 90 semi-spherical soap receptacle having a discharge orifice in its wall, a diaphragm closing the open side of said receptacle, pressure on said diaphragm discharging the soap through said orifice, and a suitable support 95 whereon said receptacle is pivoted.

3. A soap dispenser comprising an arm having means for mounting it on a suitable support, a cup pivoted on said arm and adapted to contain a supply of soap, a thin 100 metallic plate closing the open side of said cup and normally in a vertical position and forming a diaphragm, the wall of said cup having a soap discharge orifice through which the soap is delivered when pressure 105 is applied to said diaphragm.

4. A soap dispenser comprising a cup-shaped receptacle having means on its wall for pivotal connection with a suitable support, a cover diaphragm closing the open 110

side of said receptacle and normally assuming a substantially vertical position when the cup is not in use, the lower wall of said cup having a plug provided with a discharge orifice and means for regulating the flow of soap therethrough, pressure on said cover operating to discharge the soap through said orifice.

5. A liquid soap dispenser comprising a semi-spherical soap receptacle having an open side, a diaphragm closing the open side of said receptacle, said diaphragm being in the form of a comparatively thin metallic

sheet fitting into said receptacle adjacent said orifice and normally supported in a substantially vertical plane, said receptacle having a filling opening and a discharge orifice in its wall through which the soap is discharged when pressure is applied to said diaphragm, and means attached to a suitable support and whereon said receptacle is mounted.

In witness whereof, I have hereunto set my hand this 2nd day of March, 1917.

GEORGE H. HOHNSBEEN.

Copies of this patent may be obtained for five cents each, by addressing the "Commissioner of Patents, Washington, D. C."
